PLASTIC FISH BAIT

Thomas G. Faulkner, Tampa, Fla.

Application May 25, 1954, Serial No. 30,657

Term of patent 14 years

(Cl. D31—4)

FIG. 1

FIG. 2

FIG. 3

To all whom it may concern:

Be it known that I, Thomas G. Faulkner, a citizen of the United States, residing at Tampa, State of Florida, have invented a new, original, and ornamental Design for a Plastic Fish Bait, of which the following is a specification, reference being had to the accompanying drawing, forming a part hereof.

Figure 1 is an enlarged side elevational view of a plastic fish bait showing my new design; while

Figure 2 is a top plan view of the same.

Figure 3 is an enlarged view showing the front of the fish bait.

I claim:

The ornamental design for a plastic fish bait, as shown.
